UNITED STATES PATENT OFFICE.

HARRY M. SCHaab, OF YOUNGSTOWN, OHIO, ASSIGNOR OF ONE-HALF TO W. BRUCE OGDEN, OF YOUNGSTOWN, OHIO.

MAKING OPEN-HEARTH-FURNACE BOTTOMS.

Application filed February 21, 1920. Serial No. 360,468.

To all whom it may concern:

Be it known that I, HARRY M. SCHaab, a citizen of the United States, residing at Youngstown, in the county of Mahoning and 5 State of Ohio, have invented a new and useful Improvement in Making Open-Hearth-Furnace Bottoms, of which the following is a full, clear, and exact description, reference being had to the accompanying drawings, 10 forming part of this specification, in which—

Figure 1 is a side elevation partly in section of one form of apparatus in which the invention is embodied.

Figure 2 is a plan view of the apparatus 15 shown in Figure 1.

Figure 3 is a vertical section along the line III—III of Figure 2.

Figures 4 and 5 are diagrammatic views 20 of an open hearth furnace showing the application thereto of the crushed dolomite, Figure 4 being a vertical section and Figure 5 being a horizontal section through the open hearth furnace, and

Figure 6 is a side elevation of a modified 25 form of apparatus embodying the invention.

The present invention relates to making open hearth furnace bottoms, and more particularly to the building up of the furnace bottom with crushed dolomite between heats.

30 In making steel by the open hearth furnace process, a pool or bath of metal is heated in the open hearth furnace. The bottom of the furnace is lined with dolomite so that the metal is subjected to the action of the basic dolomite. During the heat more or less of the dolomite is melted into slag, so that after 35 a heat is tapped from the furnace, the dolomite bottom of the furnace has to be renewed.

40 The present invention relates to the making of the furnace bottoms mechanically and has for its object the doing away with the hand labor heretofore employed and for making the furnace bottoms much more 45 quickly and economically.

In making a furnace bottom I apply the dolomite by means of compressed air. The dolomite is projected into the furnace through a nozzle which may be so manipulated 50 as to throw or spray the dolomite over the furnace bottom. During the bottom making operation, the heat is maintained on the furnace so that the bottom is maintained in a fluxed or semi-fused condition, so that 55 the small pieces of crushed dolomite stick

against and become fused to the point on the furnace bottom against which the stream of dolomite from the nozzle is directed.

Referring first to Figures 4 and 5, an open hearth furnace 2 is diagrammatically illustrated therein. The furnace has the bottom 3 of dolomite, Figures 4 and 5 diagrammatically showing the making of such bottom. The crushed dolomite is thrown or projected into the furnace from a nozzle 4 by means of a stream of compressed air forced through the nozzle. As shown in Figures 4 and 5, the stream or spray 5 of crushed dolomite, indicated in dotted lines, may be directed as desired against the bottom of the furnace, to build up the usual furnace bottom to hold the bath of molten steel.

As shown in Figures 4 and 5, the nozzle 4 is directed through the usual door 6 in the side of the furnace. During the spraying of the dolomite into the furnace, the furnace is strongly heated by the usual gas flame, so that the dolomite is fused or sintered into an integral furnace bottom capable of holding the bath of metal. The heat holds the bottom which is already laid in a sticky semi-fused condition, so that the pieces of dolomite, as they are thrown in by the compressed air, lodge against such surface and are held thereby and then become fused into the furnace bottom. In this way the furnace bottom is quickly built up into the desired thickness and shape. The dolomite is used crushed as usual in this industry, that is, it is crushed to about the size of a pea.

In Figures 1, 2 and 3 is illustrated one form of apparatus for applying the dolomite to the furnace bottom. In this form of the apparatus the dolomite is carried in a hopper car 10 which runs on the usual rails 11 in front of the open hearth furnace or furnaces. The car is provided with two hoppers 12 and 13. The car is provided with two hoppers because both raw and burned dolomite are usually used in making a furnace bottom. Since more raw dolomite is usually used the hopper 12 for holding the raw dolomite is made somewhat larger than the hopper 13 which holds the burned dolomite. The hoppers 12 and 13 are provided at their bottoms with valves or gates 14 and 15, respectively, through which the dolomite may be drawn into the apparatus which feeds it to the furnace. The hoppers 12 and 13 open to a screw conveyer 16 which feeds

- the dolomite uniformly through the downwardly directed feed pipe 17, into the air pipe 18. The screw conveyer 16 is run by a motor 19 carried on the car.
- 1 The dolomite as it falls through the feed tube 17 into the air tube 18 is picked up and carried in the air tube by means of a stream of compressed air. The compressed air is supplied to the air tube 18 by means 10 of a pipe 20 which is connected with the compressed air supply of the steel plant. Air under fifty to one hundred pounds pressure is usually available. The stream of air and dolomite passes through a flexible hose, 15 usually a flexible steel hose, to the nozzle 4 from which the stream of dolomite is thrown or shot forcibly into the furnace. The flexible hose 21 permits the nozzle to be manipulated as desired by the operative.
- 20 The end of the hose 21 is supported on an arm 22 pivoted at 23 to the frame of the car 10 and adjustably supported by means of a rope 24 which is wound on a hand reel or windlass 25.
- 25 In making the furnace bottom the hopper car 10 filled with crushed dolomite is run in front of the furnace to be bottomed. The proper amount and kind of dolomite is fed by the manipulation of the valves 14 and 30 15 at the bottom of the hoppers. The screw conveyer 16 feeds the dolomite evenly to the compressed air pipe, and the compressed air projects or sprays the dolomite in a stream which is directed at will by the operator.
- 35 As shown in the drawings, the nozzle 14 is preferably flattened so that the stream of dolomite is spread out somewhat, as it is found that it is thus best applied to the furnace bottom.
- 40 In Figure 6 is illustrated a modification in which the hopper holding the dolomite is arranged to be swung from a crane instead of carried on a car. As shown in Figure 6 a single hopper is provided. This hopper 45 30 is provided with trunnions 31 by means of which it may be supported by an overhead crane. The dolomite is fed through a feed pipe 32 controlled by a manually operated valve 33 into the pipe 34 through 50 which compressed air is rapidly passing. The compressed air is supplied by means of a flexible hose connection 35, from the compressed air system of the steel plant. The nozzle 4 is carried on the end of a flexible

hose 21 substantially as illustrated in Figures 1 and 2. The end of the hose 21 is supported on an arm 42 pivoted to the side of the hopper and raised or lowered by means of a rope 43 controlled by a hand windlass 44.

I have described the building up of the furnace bottom from dolomite because dolomite is the material now universally employed in making furnace bottoms. It is to be understood, however, that the invention is not necessarily limited to the specific material, dolomite, but might be employed with other materials if other materials are used for making furnace bottoms. The term "dolomite" therefore, as employed in the specification and claims is intended as a term of description and not of limitation, and to include dolomite or equivalent materials which might be used in making furnace bottoms.

75 While I have specifically illustrated and described the preferred embodiment of my invention, it is to be understood that the invention is not limited to such embodiment but may be otherwise embodied within the scope of the following claims.

I claim:

1. The method of making open hearth furnace bottoms which consists in directing a stream of gaseous fluid into the furnace and against the portion of the furnace which is to be repaired from a point outside the furnace, and introducing crushed dolomite to the stream while maintaining a dolomite fusing heat in the furnace, the dolomite being introduced to the fluid stream in such manner that all particles of the dolomite will be immediately subjected to the action of the fluid stream, substantially as described.

2. The method of making open hearth furnace bottoms which consists in directing a stream of compressed air into the furnace from a point outside the same, and introducing a stream of crushed dolomite into the stream of compressed air while maintaining a dolomite fusing heat into the furnace, the stream of compressed air being at least as wide as the stream of crushed dolomite, substantially as described.

105 In testimony whereof I have hereunto set my hand.

HARRY M. SCHaab.
